UNITED STATES PATENT OFFICE.

JAMES R. ZENTZ, OF LOS ANGELES, CALIFORNIA, ASSIGNOR OF ONE-HALF TO EDGAR B. McCORMICK, OF LOS ANGELES, CALIFORNIA.

DESIGN FOR A CATAFALQUE.

Application filed November 29, 1926. Serial No. 19,873. Term of patent 3½ years.

To all whom it may concern:

Be it known that I, JAMES R. ZENTZ, a citizen of the United States of America, residing at Los Angeles, in the county of Los Angeles and State of California, have invented a new, original, and ornamental Design for Catafalques, of which the following is a specification, reference being had to the accompanying drawing, forming part thereof.

Figure 1 is a front elevation of a catafalque showing my new design;
Fig. 2 is a rear elevation thereof.
Fig. 3 is a perspective view thereof.
I claim:
The ornamental design for a catafalque, as shown.

J. R. ZENTZ.
